(57) **CLAIM**

The ornamental design for an LED light bulb, as shown and described.

DESCRIPTION

FIG. 1 is a top perspective view of an LED light bulb showing our design;

FIG. 2 is a bottom perspective view thereof;

FIG. 3 is a front elevational view thereof, the rear, left side and right side views each being the same as the front view;

FIG. 4 is a top plan view thereof;

FIG. 5 is a bottom plan view thereof;

FIG. 6 is a perspective view similar to FIG. 1 but showing a variation of our design;

FIG. 7 is a perspective view similar to FIG. 1 but showing a further variation of our design;

FIG. 8 is a top plan view of the bulb of FIG. 7; and,

FIG. 9 is a perspective view similar to FIG. 1 but showing still another variation of our design.
